UNITED STATES PATENT OFFICE

2,105,854

BUILDING

Frederick W. Buck, Washington, D. C.

Application April 3, 1937, Serial No. 134,922

7 Claims.

(CL. 72—1)

This invention relates to certain new and useful improvements in buildings.

The primary object of the invention is to provide a building preferably of concrete construction wherein base and head rails are connected by vertical standards or posts with anchor rods for securing the rails and posts together, the outer side wall and roof structure comprising inter-fitting concrete slabs mounted in a manner to permit limited expanding and contracting movements with an air-tight seal between the slabs.

A further object of the invention is to provide a concrete building of the foregoing character wherein the wall and roof are formed of concrete slabs inter-fitting at adjacent side edges with a folded copper strip having the free edges thereof respectively anchored to the edges of adjacent slabs and presenting contacting flat portions of the copper strip that relatively move in contact with each other during expanding and contracting movements of the concrete slabs to maintain an air-tight seal between the adjacent edges of the concrete slabs.

A still further object of the invention is to provide a concrete building structure wherein the side walls are formed of concrete slabs, extending from the head to the base rails of the building structure, except for door and window openings with an interfitting connection between adjacent side edges of the wall slabs and the upper ends of the slabs and the head rail of the building structure with a metallic sealing strip, preferably formed of copper folded upon itself with the free edges thereof respectively attached to adjacent portions of the element with sections of the copper strip having flat contacting surfaces adapted to rub over each other during expanding and contracting movements of the concrete slabs to maintain a sealed connected between the building element.

With the above and other objects in view that will become apparent as the nature of the invention is better understood, the same consists in the novel form, combination and arrangement of parts hereinafter more fully described, shown in the accompanying drawings and claimed.

In the drawings:—

Figure 1 is a fragmentary front elevation, partly in section, of a concrete building constructed in accordance with the present invention;

Figure 2 is a vertical cross-sectional view taken on line 2—2 of Figure 1, showing the connection between the side wall concrete slabs and the base

and head rails of the building and the mounting of the roof rafters with the concrete roof slabs thereon;

Figure 3 is an enlarged horizontal detail sectional view taken on line 3—3 of Figure 2, showing the bracing devices for the corner posts;

Figure 4 is a vertical fragmentary sectional view showing the tie rods extending through the corner posts and anchored at their ends to the base and head rails and the expandable connections between the upper ends of the side wall slabs and the head rails;

Figure 5 is a detail sectional view taken on line 5—5 of Figure 2, showing the expandable connection between the adjacent edges of the roof slabs;

Figure 6 is an enlarged detail sectional view taken on line 6—6 of Figure 1, showing the manner of supporting the roof rafters on the head rails of the building structure;

Figure 7 is a fragmentary top plan view of connected ends of two head rails;

Figure 8 is a detail sectional view taken on line 8—8 of Figure 7, showing the inter-fitting connection between adjacent ends of the two head rails and the tie rods for anchoring the head rails to the vertical posts;

Figure 9 is a fragmentary perspective view of a metallic strip to form a sealed connection between adjacent side edges of the side wall and roof slabs;

Figure 10 is a fragmentary perspective view showing the metal strip to form a sealed connection between the upper ends of the side wall slabs and the head rails of the building structure.

Referring more in detail to the accompanying drawings, the building structure is supported upon a concrete or other foundation 15 and the building structure herein disclosed for purposes of illustration is of generally rectangular formation in plan view embodying base rails 16 seated on the foundation 15. Corner posts 17 perpendicularly rise from the base rails 16 and support horizontal head rails 18 at their upper ends, a roof structure 19 being supported on the head 45 rails. Vertical walls 20 are disposed between the base and head rails 16 and 18 and the corner posts 17 and as the head rails 18 are supported on the corner posts 17, the side walls 20 are free of any supporting weight so that the block or flat structure of the side walls to be later described are not subjected to undue weight or strain.

The base and head rails 16 and 18 are locked as by tie bolts to the corner posts 17 and these

- connected elements are anchored by the same tie bolts to the foundation 15, the lower ends of the corner posts 17 being supported on the base rails 16 while the adjacent upper ends of the head rails 18 are mitered as at 22 to form an interfitting connection as shown in Figs. 7 and 8. Reinforcing tie rods 23 are embedded in the corner posts 17 and extend longitudinally thereof, the lower ends of the tie rods 23 extending 10 through the base rails 16 and having their lower headed ends 24 embedded in the foundation 15 while the upper ends of the tie rods extend through the mitered ends 22 of the interfitting ends of the head rails 18 with the terminal upper 15 ends of the tie rods threaded for the reception of nuts 25.
- Inclined anchor and brace devices extend between the base rails 16 and corner posts 17 and as shown more clearly in Figs. 2 to 4, an anchor 20 rod 26 having an eye 27 at each end respectively engaged with eye bolts 28 and 29 respectively anchored in the base rails 16 at points spaced from the ends thereof and in the corner posts 17 intermediate the upper and lower ends thereof.
- 25 The side walls 20 are preferably formed of vertically disposed elongated slabs 30, some of which are provided with window and door frames, window sashes being shown at 31, the lower ends of the side wall slabs 30 being slightly bevelled as 30 at 32 as shown in Figure 4 with the lower ends of the slabs seated in longitudinally extending ledges 33 at the upper outer edges of the base rails 16, a plastic cement or mastic sealing the joints between the lower ends of the slabs and the bottom walls of the ledges 33. The slabs 30 are preformed and are provided with mitered side edges 34 and a mitered upper end 35. A folded metallic strip, preferably formed of copper is associated with adjacent interfitting mitered edges 40 of the side wall slabs 30 with the free edges of the folded copper strips anchored to the inner faces of two adjacent slabs as by plastic cement, mastic or the like, with the folded portion of the strip positioned between the mitered inter-connection 45 between adjacent edges of two slabs and presenting flat faces of the copper strip in rubbing contact with each other so that the concrete side wall slabs may laterally expand and contract with a sealed joint between the interfitting mitered edges of the slabs maintained.
- 50 As shown more clearly in Figures 3 and 9, the copper strip is folded upon itself to provide a pair of oppositely directed free side edges 36 anchored to the inner faces of adjacent edges 55 of the side wall slabs 30 with the folded portion of the copper strip presenting two flat contacting surfaces 37 lying in a plane offset from and parallel with the plane of the side free edges 36 and with the folded edge 38 of the strip directed 60 outwardly at right angles from the flat contacting surfaces 37. The folded edge 38 of the copper strip terminates inwardly of the outer faces of the concrete slabs 30 and may be covered by a plastic cement or mastic 39 if desired, and as 65 shown in Figure 3.
- The mounting for the upper ends of the side wall slabs 30 is shown more clearly in Figs. 4 to 6 and 10, the lower face of the head rail 18 having the stepped recess 40 therein adjacent the front face of the rail that extends longitudinally thereof for reception of the stepped upper ends 41 of the side wall slabs 30, the lower face of the head rails also having another longitudinally extending groove or recess 42 therein to dissipate the 70 transfer of moisture from the outer face of the head rail to the inner face thereof. A molded metallic strip, preferably formed of copper and shown in detail in Fig. 10 is interposed between the stepped recess 40 in the head rail 18 and the upper ends 41 of the side wall slabs 30, the folded strip being of substantially inverted U-shape in cross-section with the upper closed end of stepped formation as shown at 43 with parallel side sections, one side section comprising relatively free contacting strips 44 and 45 while the other side section comprises contacting strips 46 connected by an edge bead 47. The strip 44 is anchored to the adjacent wall of the socket 42 while the strip 45 is anchored to the inner face of the upper end of the side wall slabs 30, the folded strips shown in Figure 10 being initially assembled in the stepped recess 40 and anchored therein with the upper ends of the side wall slabs 30 thereafter positioned in said folded strips.
- The detail construction of the roof 19 includes 20 concrete rafters 48 notched at their upper ends as shown in Figure 2 and mounted upon the ridge bars 49 with the lower forward ends of the rafters supported on the head rails 18 and projecting beyond the rails as shown in several of the figures. The head rails 18 have transverse grooves 25 therein for the reception of the rafters 18 and said rafters are shouldered as at 50 for abutting engagement with portions of the head rails for holding the rafters in position, the latter being further anchored to the head rails by tie wires 51 anchored in the head rails and extending over the rafters as illustrated in several of the figures. Concrete roof slabs 52 are laid upon the rafters 48 and may be mounted to extend either longitudinally or transversely of the rafters, the forward projecting ends of the rafters having rearwardly directed hook portions 53 for receiving the lower forward ends of the roof slabs. A folded metal strip of the construction shown in Figure 9 connects adjacent edges of the roof slabs as illustrated in Figures 1 and 5, while said roof slabs are further anchored to the head rails 18 by U-shaped copper strips 54 having the side portions thereof contacting each other with one portion anchored to a bevelled surface of the head rail 18 while the other portion is anchored to the under face of the roof slab 52.
- The inner upper edges of the base rails 16 are mitered to facilitate the mounting of inter-fitting 50 concrete floor boards 55 and upon which wooden or other flooring may be laid. As shown in Figure 3, a copper sheathing strip covers the inner faces of the corner posts 17 to prevent the passage of moisture from the outer sides of the corner posts to the inner sides thereof while vertical wall boards are set into the inner mitered edges of the base rails 16 to provide an air space between the side wall slabs 30 and the inner wall construction and which may be filled with a suitable insulating material.
- The side wall structure 20 has the slabs thereof inter-fitting and mounted in a manner to permit horizontal and vertical expanding and contracting movement, the inter-fitting connections between the side wall slabs 30 and the upper ends of the side wall slabs and head rails including the folded copper strips that have sections rubbing over each other so that an air-tight seal is established at all times between the joints of the several sections of the side wall structure. In a similar manner, the roof slabs 52 are permitted to expand and contract with the joint between adjacent slabs remaining in a sealed condition. It is to be understood that the wall and roof 75

slabs may be reinforced in any appropriate manner, as by inbedded reinforcing rods 57 as shown in several of the figures.

From the above detailed description of the invention, it is believed that the construction and operation thereof will at once be apparent and while there is herein shown and described the preferred embodiment of the present invention, it is nevertheless to be understood that minor changes may be made therein without departing from the spirit and scope of the invention as claimed.

I claim:—

1. In a building of the character described, a wall structure including vertical posts, and head and base rails, wall plates mounted between the posts and rails, an expansible joint between the vertical sides of the plates and the upper ends of the plates and head rails, each joint including an inter-fitting connection between the rails and plates and a folded metallic strip having the free edges thereof respectively secured to adjacent edges of relatively movable parts with the folded portion of the strip being confined in the inter-fitting connections and presenting flatly contacting relatively movable portions.

2. In a building of the character described, a wall structure including vertical posts, and head and base rails, wall plates mounted between the posts and rails, an expansible joint between the vertical sides of the plates, each joint including a folded metallic strip with the free edges thereof respectively secured to adjacent edges of relatively movable parts, the metallic strip embodying flatly contacting strip sections adapted to frictionally move over each other and maintain the sealed connection between the parts during expanding and contracting movements thereof.

3. In a building of the character described, a wall structure including vertical posts, and head and base rails, wall plates mounted between the posts and rails, an expansible joint between the vertical sides of the plates, each joint including a folded metallic strip with the free edges thereof respectively secured to adjacent edges of relatively movable parts, the folded edge of the strip being disposed between adjacent edges of the plates and spaced inwardly of the outer faces of the plates and a mastic filling between the edges of the plates overlying the folded edges of the strips.

4. In a building of the character described, a wall structure including vertical posts, and head and base rails, wall plates mounted between the posts and rails, an expansible joint between the vertical sides of the plates, each joint including

a folded metallic strip with the free edges thereof respectively secured to adjacent edges of relatively movable parts, the metallic strip embodying flatly contacting strip sections adapted to frictionally move over each other and maintain the sealed connection between the parts during expanding and contracting movements thereof, the folded edge of the strip being disposed between adjacent edges of the plates and spaced inwardly of the outer faces of the plates and a mastic filling between the edges of the plates overlying the folded edges of the strips.

5. In a building of the character described, a wall structure including horizontal head and base rails, perpendicular posts rigidly connecting the head and base rails providing side wall areas and side wall plates mounted in the side wall areas and interconnected with each other and with the head and base rails whereby the plates are free to expand and contract in horizontal and perpendicular directions and a roof structure supported on the head rails, the connection between the side wall plates including metallic elements having portions anchored to adjacent edges of two plates and other portions flatly contacting each other and relatively movable during expanding and contracting movements of the plates to maintain a sealed connection between adjacent edges of the plates.

6. In a building of the character described, a wall and roof structure including skeleton frames, plates supported in the frames, and an expansible joint between adjacent edges of the plates including a folded metallic strip with the free edges thereof respectively secured to the edges of adjacent plates, the metallic strip embodying flatly contacting strip sections adapted to frictionally move over each other and maintain a sealed connection between the plates during expanding and contracting movements thereof.

7. In a building of the character described, a wall and roof structure, the roof structure comprising inclined rafters, head rails for supporting the lower ends of the rafters and having an interlocking engagement therewith, roof plates supported on the rafters and an expansible joint between the side edges of adjacent roof plates including a folded metallic strip with the free edges thereof respectively secured to the edges of adjacent plates, the metallic strip embodying flatly contacting strip sections adapted to frictionally move over each other and maintain a sealed connection between the plates during expanding and contracting movements thereof.

FREDERICK W. BUCK.
